UNITED STATES PATENT OFFICE.

WALTER H. COTTON AND CLARENCE H. KEHM, OF CHICAGO, ILLINOIS.

AIR-VALVE CAP.

1,326,647.

Specification of Letters Patent. Patented Dec. 30, 1919.

Application filed June 28, 1919. Serial No. 307,322.

To all whom it may concern:

Be it known that we, WALTER H. COTTON and CLARENCE H. KEHM, citizens of the United States, and residents of Chicago, 5 county of Cook, and State of Illinois, have jointly invented certain new and useful Improvements in Air-Valve Caps, of which the following is a specification, and which are illustrated in the accompanying drawings, forming a part thereof.

The escape of steam from the usual form of air valve as used on steam radiators has been a cause of great annoyance. The sound of the escaping gas has been irritating and 15 the rising current of air mingled with the steam and moisture resulting therefrom has rapidly disfigured the decoration of the walls adjacent the radiator.

The object of the present invention is to 20 avoid this annoyance by providing a cap for air valves that shall direct escaping gases downwardly and retain any free moisture escaping therewith in such a manner as to give the same out slowly to humidify the 25 atmosphere without irritating sound or disfigurement of walls.

Preferred embodiments of the invention are illustrated in the drawings in which:

Figure 1 is an elevation of a portion of 30 a radiator section and an air valve with a valve cap in section,

Figs. 2 and 3 are horizontal sections on lines 2—2 and 3—3 respectively of Fig. 1,

Fig. 4 is a central vertical section of a 35 different form of the invention.

A portion of a radiator section is shown at 10 and a common form of air valve at 11, having a thread at 12 for reception of a cap. The vent of the valve is designated at 13.

To prevent the flow of gases upward a 40 shell or cap 14 is provided which, in the form of the invention illustrated in Figs. 1 to 3, is dome shaped. The lower portion of the shell is closed by a diaphragm 15 provided with a screw threaded opening 16 at 45 its center for attachment to the valve.

Gases vented from the valve into the cap 50 are permitted to escape therefrom by means of vent openings 17 shown in Fig. 2 as being four in number. To prevent any free moisture escaping with the gases a drip cup, as 55 18, is shown which in the form illustrated, is annular and spaced at its inner portion from the air valve and co-operating screw threaded portion of the cap, as at 19.

To absorb free moisture and prevent hissing sounds, the interior of the shell is shown as filled with absorbent material, preferably cotton gauze, as 20.

In the form of the invention illustrated 60 in Fig. 4, the shell assumes, in general, the form of a cylinder, as at 21, with the drip or moisture receiving cup integral with the lower portion thereof, as at 22. The drip cup is continued upward and inwardly to 65 provide the threaded opening 23 for attachment to the air valve.

The shell in this form of the invention is shown as closed at the top by a cover 24 adapted to screw upon the shell and provided with a skirt, at 25, offset outwardly 70 from the shell to provide space 26 thereabout. Vent openings 27 are shown opening into this space whereby the escaping steam or gases will be directed downwardly 75 by the depending skirt. As with the form of the invention of Figs. 1 to 3, that of Fig. 4 is provided with a filling of absorbent material, indicated at 20, for the purpose described.

It will be seen that there are disclosed 80 embodiments of an invention that will attain the objects specified and that various changes in details thereof may be made without departing from the spirit of the 85 invention.

We claim as our invention:

1. In combination, an air valve for a steam radiator, a cap for said valve comprising an impermeable shell, said shell 90 having downwardly directed vent openings.

2. In combination, an air valve for a steam radiator, a cap for said valve comprising an imperforate upper surface and having vent openings adapted to direct escaping gases downwardly and an absorbent material in said shell.

3. In combination, an air valve for steam radiators, a cap for said valve comprising a shell having vent openings at its lower 100 portion, and a moisture-receiving cup exterior to said vent openings.

4. An air valve cap comprising a shell imperforate at its upper surface, having vent openings, means to direct vented matter downwardly, and means to attach said shell to a valve.

5. An air valve cap comprising a shell imperforate at its upper surface, having vent openings, means to direct vented mat- 110

ter downwardly, and means to attach said shell to a valve, said shell being filled with absorbent material.

6. An air valve cap, comprising a shell having an imperforate upper surface and downwardly directed perforations in its lower portion, a drip cup below said perforations, and means for attachment of said shell to an air valve.
- 10 7. An air valve cap comprising a shell having an imperforate upper portion and downwardly directed perforations in its lower portion, a drip cup below said perforations, a filling of absorbent material in said shell, and means for attaching said shell to an air valve.
- 15 8. An air valve cap comprising a sub-

stantially hemispherical shell, a diaphragm closing said shell having a screw threaded opening adapted to be applied to an air valve and vent openings adjacent said screw threaded opening.

9. An air valve cap comprising a substantially hemispherical shell, a diaphragm closing said shell having a screw threaded central opening for attachment of the cap to a valve and vent openings near the margin, an annular drip cup semi-cylindrical in cross section secured below said vent openings and a filling of absorbent material in said shell.
